US0D1051052S

(12) **United States Design Patent** (10) **Patent No.:** **US D1,051,052 S**
(45) **Date of Patent:** **** Nov. 12, 2024**

(54) **BATTERY CHARGER**

(71) Applicant: **Shenzhen Changyi Technology Co., Ltd.**, Guangdong (CN)

(72) Inventor: **Hanxiu Ma**, Suzhou (CN)

(73) Assignee: **Shenzhen Changyi Technology Co., Ltd.**, Shenzhen (CN)

(**) Term: **15 Years**

(21) Appl. No.: **29/954,066**

(22) Filed: **Jul. 25, 2024**

(51) LOC (14) Cl. **13-02**

(52) U.S. Cl.

USPC **D13/108**

(57) **CLAIM**

The ornamental design for a battery charger as shown and described.

DESCRIPTION

FIG. 1 is a top, front and left side perspective view of a battery charger, showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the battery charger that form no part of the claimed design.

1 Claim, 8 Drawing Sheets
